CLAIM

The ornamental design for an actuator for an aerosol can device, as shown and described.

DESCRIPTION

The application relates to an actuator for use with an aerosol can device.

FIG. 1 is a perspective view of an actuator for an aerosol can device showing our new design;

FIG. 2 is a front view thereof;

FIG. 3 is a rear view thereof;

FIG. 4 is a right side view thereof;

FIG. 5 is a left side view thereof; and,

FIG. 6 is a top plan view thereof.

The broken lines in FIG. 6 define boundaries of the claimed design and form no part of the claimed design.
